NITRATION OF AROMATIC HYDROCARBONS

Josef Meissner, Burbach kreis Siegen, Germany

Application October 31, 1935, Serial No. 47,727
In Germany November 28, 1934

4 Claims. (Cl. 260—645)

This invention relates to improvements in the nitration of aromatic hydrocarbons. The object of the invention is to provide a process which allows continuous nitration of hydrocarbons and which has the advantage that a safe operation and a good output are obtained while using an apparatus of very small dimensions.

Heretofore nitroproducts of the kind referred to have been produced in a relatively large apparatus and by methods employing a number of separate operations. These methods were disadvantageous in that it was very difficult to dissipate the heat of reaction and to reduce the time of reaction to a minimum. Other disadvantages such as incomplete mixing of the nitrating mixture and insufficient accessibility of the nitrating acid to the aromatic hydrocarbons to be nitrated are of special note. These disadvantages are of great influence on nitration processes and reduce their output considerably.

With the new process it is possible to nitrate the aromatic hydrocarbons thoroughly in one working step, and to avoid the drawbacks referred to above completely.

The new process consists in continually introducing the hydrocarbons to be nitrated into the upper part of a vessel which is provided with a pipe cooling system and in continually introducing the nitrating acid into the lower part of said vessel whereby a forced circulation is obtained within the vessel, the nitrated material being discharged at the upper part of the nitrating vessel. By this arrangement a preliminary nitration is obtained in the upper part of the vessel as, at this point, the nitrating acid which has been introduced at the lower part of the nitrating vessel has been partly consumed and therefore diluted, whereas the final nitration takes place in the lower part of the vessel where the fresh nitrating acid is introduced. In order to obtain a complete mixture of the nitrating components and to produce an emulsion of the nitrating mixture by the introduction of finely divided air, the mixture within the nitrating vessel is stirred by an agitating device which has a mixing propeller at its lower part and vanes for emulsifying purposes at its upper part.

A preferred embodiment of an apparatus for carrying out the new nitration process is illustrated in the accompanying drawing by a sectional view.

Referring to the drawing, a nitrating vessel is shown provided with a pipe cooling system 6 and an agitating device 3. This agitating device carries a mixing propeller 4 at its lower part and

vanes 5 for emulsifying the mixture at its upper part. At the bottom of the vessel a valve 2 is provided for introducing the nitrating acid, whereas a pipe 1 is provided at the upper part of the vessel for introducing the hydrocarbons to be nitrated. The mixture is discharged through the port 7. Inlet 8 and outlet 9 respectively serve for introducing the cooling medium into the cooling system 6 and for discharging the cooling medium from such cooling system.

After the apparatus has been filled with nitrating acid the material to be nitrated, as for example toluene, is introduced through the pipe 1. At the same time the agitating device is started in order to obtain a complete mixture of the components, which is very essential for efficient nitration. By the action of the agitating device, the mixture is not only stirred but also emulsified as air is introduced into the nitrating mixture in a finely divided state. This causes a subdivision of the nitrating mixture into small drops, whereby a greater nitrating surface is produced. This, in turn, causes an acceleration of the nitration process and a more uniform product. It was found that by emulsifying the mixture with air the formation of nitric oxides could be disposed of almost entirely.

The air which is distributed in the mixture in a very finely divided state makes possible a very quick separation of the nitrated material from the adhering waste acid in the separator (not shown). By introducing the nitrating acid into the lower part of the nitrating vessel at 2 the nitrating acid, which is diluted by the preliminary nitration, is replaced by the fresh acid and a final nitration is obtained at this point. This final nitration could previously only be obtained by a process employing several separated steps.

The fact that the nitrating mixture is forced through the space between the cooling system 6 during the nitration process is of special importance. In this way the heat of reaction is dissipated more rapidly than has heretofore been possible in the known nitrating devices.

The nitrating mixture discharged at the upper part of the vessel through the opening 7 is proportional to the amount of aromatic hydrocarbons introduced into the upper part of the nitrating vessel and the amount of nitrating acid introduced into the lower part of said vessel.

The advantages obtained with the new process may be shortly summarized as follows:

1. Continuous nitration by circulating the nitrating mixture.
2. Great nitrating surface by intensively stir-

ring the nitrating mixture with an agitating device having a mixing propeller and vanes for emulsifying purposes.

3. Prevention of the formation of nitric oxides by emulsifying the nitrating mixture with air.
4. Accelerated separation of the nitrated mixture in the separator caused by the presence of the air which has been distributed in a finely divided state in the mixture.
10. 5. Intensive cooling of the finely divided nitrating mixture in the nitrating vessel because of the pipe cooling system.
6. Large output of a nitrating apparatus which has small dimensions, this feature being of special advantage when working with explosives.

What I claim is:

1. In a process for the continuous nitration of aromatic hydrocarbons the steps comprising introducing the material to be nitrated into the upper part of a vessel, introducing into said vessel a cooling fluid in heat exchange relation with the reactant material but not in direct contact therewith, introducing the nitrating acid into the lower part of said vessel, providing a forced circulation of the ensuing mixture in a downward and upward direction said circulation causing partly consumed nitrating acid to come into contact with the fresh material to be nitrated which is introduced into the upper part of the vessel to 25 effect a preliminary nitration thereof, and said circulation causing such preliminarily nitrated material to come into contact with the fresh nitrating acid which is introduced into the lower part of the vessel to effect final nitration thereof.
30. 2. In a process for the continuous nitration of aromatic hydrocarbons the steps comprising introducing the material to be nitrated into the upper part of a vessel, introducing into said vessel a cooling fluid in heat exchange relation with the reactant material but not in direct contact therewith, introducing the nitrating acid into the lower part of said vessel, emulsifying the ensuing mixture, providing a forced circulation of said mixture in a downward and upward direction said 35 circulation causing partly consumed nitrating acid to come into contact with the fresh material

to be nitrated which is introduced into the upper part of the vessel to effect a preliminary nitration thereof, and said circulation causing such preliminarily nitrated material to come into contact with the fresh nitrating acid which is introduced into the lower part of the vessel to effect final nitration thereof, and discharging the nitrated mixture at the upper part of the vessel.

3. In a process for the continuous nitration of aromatic hydrocarbons the steps comprising introducing the material to be nitrated into the upper part of a vessel, introducing into said vessel a cooling fluid in heat exchange relation with the reactant material but not in direct contact therewith, introducing the nitrating acid into the lower part of said vessel, heating air into the ensuing reactant mixture to emulsify the same, providing a forced circulation of such mixture in a downward and upward direction, said circulation causing partly consumed nitrating acid to come into contact with the fresh material to be nitrated which is introduced into the upper part of the vessel to effect a preliminary nitration thereof, and said circulation causing such preliminarily nitrated material to come into contact with the fresh nitrating acid which is introduced into the lower part of the vessel to effect final nitration thereof, and discharging the nitrated mixture at the upper part of the vessel.

4. In a process for the continuous nitration of aromatic hydrocarbons the steps comprising introducing the material to be nitrated into the upper part of a vessel, introducing nitrating acid into the lower part of the vessel, beating air into the mixture, circulating the portion of the mixture containing the fresh nitrating acid upwardly and in heat exchange relationship with a cooling fluid but not in direct contact therewith, contacting the ensuing partly consumed nitrating acid with the fresh material to be nitrated, and circulating such mixture downwardly to effect preliminary nitration of the fresh material to be nitrated, and discharging the nitrated mixture at the upper part of said vessel.

JOSEF MEISSNER.
